UNITED STATES PATENT OFFICE.

ALBERT PETER GILLEN, OF CHICAGO, ILLINOIS.

DESIGN FOR A PIANO-LAMP.

54,613.

Specification for Design.

Patented Mar. 9, 1920.

Application filed December 1, 1919. Serial No. 341,801. Term of patent 3½ years.

To all whom it may concern:

Be it known that I, ALBERT P. GILLEN, a citizen of the United States, residing at Chicago, in the county of Cook and State of Illinois, have invented a new, original, and ornamental Design for a Piano-Lamp, of which the following is a specification, reference being had to the accompanying drawing, in which a perspective view of the design is shown.

I claim:—

The ornamental design for a piano lamp, as shown.

In testimony whereof I affix my signature.

ALBERT PETER GILLEN.
